UNITED STATES PATENT OFFICE

ARTHUR L. WOODBRIDGE, OF CHICAGO, ILLINOIS

STAIRWAY CONSTRUCTION

Application filed March 17, 1928. Serial No. 262,547.

This invention relates to a stairway construction and has special reference to a concrete and metal stairway of a standardized construction which is adaptable for use in any building.

More particularly, this invention relates to a safety nosing to be used on stair cases of metal and concrete construction, the nosing being applied to the forward edge of the tread 10 and extending the full width thereof. Being so positioned, the nosing receives the greatest wear and it is, therefore, desirable that the nosing may be readily removed and replaced when necessary.

15 One of the objects of this invention is to provide a safety nosing for stair cases of metal and concrete construction which nosing will be supported in a manner as to not detract from the appearance of the stair and 20 will be assured against breaking away from the concrete fill.

25 A further object of this invention is to provide a safety nosing of an improved type which is renewable in a simple, convenient and inexpensive manner without disturbing the assembly of the staircase.

30 Other objects of this invention will be apparent from the description and drawing forming a part of this specification to which reference may now be had for a more complete understanding of the characteristic features of this invention, in which drawing:

Figure 1 is a perspective view partially in section of a stair case of metal and concrete 35 which embodies the features of this invention; and,

Figure 2 is a top plan view, greatly reduced, of the structure shown in Fig. 1.

Referring now to the drawing, the staircase 40 comprises tread and riser members, the latter members being preferably formed of a single sheet of metal having a tread portion 10 and a riser portion 11. These members are disposed between and supported by stringers 12. In the particular construction shown, the 45 supporting members may be angle irons 13 having one leg lying beneath the tread portion and supporting it and the other leg portion extending upwardly adjacent the stringer and secured thereto. The upper end

of the riser portion 11 projects forwardly and upwardly, the extreme upper end 14 thereof extending rearwardly in a substantially horizontal plane. The forwardly extending portion 15 of the riser 11 is preferably 55 inclined to support a forwardly inclined portion 16 of the tread 10 next above. These two inclined portions are suitably secured together as by means of bolts and nuts 17, the nut preferably being disposed on the inner 60 side of the construction.

A safety nosing 18, preferably formed in the general shape of an angle iron, is secured to the horizontally extending portion 14 of the riser and extends across the full width 65 thereof, the ends of the nosing abutting the stringers 12. The nosing is secured to the risers by means of nuts and bolts 19, the nuts being preferably disposed on the inner side 70 of the construction, that is, beneath the horizontally extending portion 14.

By reason of the tread member 10 being secured to the riser next below at a point below the upper end thereof, a recess is provided which is filled with concrete 20 or any 75 composition filling to a plane coextensive with the upper plane of the nosing 18.

It will be particularly noted that any weight disposed on the nosing 18 will be supported by the reinforced portion formed 80 by the connection of adjacent tread and riser members and indicated by the letter A, and that with this construction, the nosing will not break away from the concrete or other filling 20. The lower edge of the depending 85 portion of the nosing 18 is bevelled to conform to the inclination of the forwardly extending portion of the riser 11. By reason of the particular construction thus obtained, the bolt heads are partially concealed and an 90 even, balanced and attractive appearance is obtained when viewed in ascending the staircase. Further, by reason of the nuts of the bolts 19 being embedded in the concrete or other fill 20, these bolts may be unscrewed 95 and again screwed into position readily and easily when it is desired to renew the nosing, since the nuts are held against rotation by the filling. The nosing 18 is preferably 100 made of Feralun when it is desirable to pro-

vide a material of a long life, although it is apparent that treads of other metals may be used. Also, wood, cork and the like may be adapted as a fill for various other conditions.

As a result of this invention, a nosing is obtained which is so constructed and arranged as to be readily removed when it is desired to have the same replaced. Further, a construction is afforded whereby the nosing will not break away from the concrete or other fill when a weight or force is exerted thereon due to the nosing being supported directly over the reinforced portion indicated at A.

While but a single embodiment of this invention is herein shown and described, it is to be understood that the same is not to be limited to that specific construction since various modifications may occur to those skilled in the art without departing from the spirit and scope of this invention, and it is, therefore, desired that the same be limited only by the showing of the prior art and the scope of the appended claims.

I claim:

1. The combination with a stair structure including tread and riser sections having forwardly and upwardly inclined portions secured together in an overlying relation, of an angularly shaped nosing removably secured to the upper end of said riser section directly above said inclined portions.

2. The combination with a stair structure including tread and riser sections having forwardly and upwardly inclined portions secured together in an overlying relation, of an angularly shaped nosing removably disposed at and secured to the forward edge of said tread section and supported directly by said overlying inclined portions.

3. The combination with a stair structure including tread and riser sections having forwardly and upwardly inclined portions secured together in an overlying relation, of an angularly shaped nosing removably secured to the horizontally extending upper end of said riser section directly above said overlying inclined portions.

4. The combination with a stair structure including tread and riser sections having forwardly and upwardly inclined portions secured together in an overlying relation, of a nosing removably secured to the horizontally extending upper end of said riser section directly above said overlying inclined portions, said nosing having a depending portion in engagement with the face of said riser and extending substantially to said inclined portions.

5. The combination with a stair structure including tread and riser sections having forwardly and upwardly inclined portions secured together in an overlying relation, of an angular-shaped nosing removably secured to the horizontally extending upper end por-

tion of said riser section directly above and supported by said overlying inclined portions.

6. The combination with a stair structure including tread and riser sections connected together at the forward and upper ends respectively thereof to provide a recessed flooring to receive and to support a filling of concrete, of an angular-shaped nosing overlying an extending portion of said sections and having its upper surface flush with the upper surface of said concrete filling, and a nut embedded in said concrete filling adjacent said extending portion for receiving a screw extending therethrough and through said nosing whereby said nosing is readily removable.

7. The combination with a stair structure including tread and riser sections connected together at the forward and upper ends respectively thereof to provide a recessed flooring to receive and to support a filling of concrete, of an angular-shaped nosing overlying an extending portion of said sections and having its upper surface flush with the upper surface of said concrete filling, and a securing member having a portion thereof embedded in said concrete filling adjacent said extending portion for removably securing said nosing to said extending portion.

8. The combination with a stair structure including tread and riser sections connected together at the forward and upper ends respectively thereof to provide a recessed flooring to receive and support a filling of concrete or the like, of an angularly shaped nosing overlying an extending portion of said sections and being removably secured thereto.

9. The combination with a stair structure including tread and riser sections connected together at the forward and upper ends respectively thereof to provide a recessed flooring to receive and support a filling of concrete or the like, of an angularly shaped nosing removably positioned at the forward exposed edge of said filling.

In witness whereof, I have hereunto subscribed my name.

A. L. WOODBRIDGE.
